UNITED STATES PATENT OFFICE.

WILLIAM H. ETTER, OF MARIETTA, OHIO.

WEATHER-STRIP.

No. 824,001.

Specification of Letters Patent.

Patented June 19, 1906.

Application filed June 26, 1904. Serial No. 214,174.

To all whom it may concern:

Be it known that I, WILLIAM H. ETTER, a citizen of the United States, residing at Marietta, in the county of Washington and State of Ohio, have invented a new and useful 5 Weather-Strip, of which the following is a specification.

The invention relates to improvements in weather-strips.

10 The object of the present invention is to improve the construction of weather-strips and to provide a simple, inexpensive, and efficient one of great strength and durability designed for use on doors and windows and capable of effectually excluding the air and adapted to conform to any irregularities of a door or window.

15 A further object of the invention is to provide a weather-strip of this character adapted to be applied to a fixed portion of a door or window casing and capable of firmly clamping a door or window sash when the same is closed.

20 With these and other objects in view the invention consists in the construction and novel combination and arrangement of parts hereinafter fully described, illustrated in the accompanying drawings, and pointed out in the claims hereto appended, it being understood 25 that various changes in the form, proportion, size, and minor details of construction within the scope of the claims may be resorted to without departing from the spirit or sacrificing any of the advantages of the invention.

30 In the drawings, Figure 1 is a perspective view of a portion of a weather-strip constructed in accordance with this invention. Fig. 2 is a similar view illustrating a slight 35 modification of the invention, the felt strip or lining being omitted. Fig. 3 is a horizontal sectional view of a portion of a door-casing, illustrating the arrangement of the weather-strip and showing the position of the engaging flange when the door is open. Fig. 4 is a 40 similar view illustrating the arrangement of the clamping-flange when the door is closed.

45 Like numerals of reference designate corresponding parts in all the figures of the drawings.

50 1 designates a weather-strip constructed of resilient sheet metal and consisting of two straight flanges 2 and 3, presenting smooth flat faces at both sides and arranged at an angle to each other and adapted, respectively, to be secured to a door or window casing and

to engage the door or window sash. The flanges 2 and 3, which form an acute angle, are arranged at an angle slightly less than ninety degrees and more than forty-five degrees. The flange 2 is provided at intervals 60 with perforations for the reception of fastening devices 4 for securing the attachment-strip to a door-casing 5 or to a window-casing. (Not shown.) The attachment or stationary flange is arranged flat against the inner side face of the door-casing, and the clamping-flange is arranged contiguous to the abutting face 6 of the strip or portion 7, against which the door 8 abuts, and when the door 8 is closed it engages the clamping-flange and flexes or bends the same backward against the abutting face 6 to a position at right angles to the attachment-flange, whereby the clamping-flange is caused to 75 firmly engage the door. The clamping or movable flange is resilient and is adapted to readily yield or conform to any irregularities of a door or window, and in order to enable it to fit closely and effectually close any crevices it is provided at its engaging face with a lining 9, consisting of a strip of felt or other suitable fabric. When the door is closed, the stationary or attachment flange is arranged at the outer or free edge of the door, and the 80 movable or clamping flange engages one of the side faces of the door.

It will be seen that the weather-strip is exceedingly simple and inexpensive in construction, that it is light, strong, and durable, and 90 that it is adapted to be readily applied to a door or window casing. Also it will be clear that when the door or window is closed the clamping-flange is flexed or bent from its normal position and owing to the resiliency of 95 the material of which the weather-strip is constructed firmly engages the door or window. Furthermore, it will be apparent that the strip of felt, which forms the yieldable lining for the clamping-plate, effectively engages a door or window and that it is supported by the clamping-flange throughout 100 its entire area, whereby its durability will be much greater than the projecting unsupported portion of felt strips of many weather-strips.

Having thus fully described my invention, what I claim as new, and desire to secure by Letters Patent, is—

1. A weather-strip constructed of resilient 110 material bent longitudinally to form two straight longitudinal flanges of regular form,

which present smooth flat faces to the surface against which the strip is to be applied, said flanges being arranged at an angle to each other, which angle is less than ninety degrees and more than forty-five degrees, one of the flanges forming an attachment-flange secured rigidly in place, and the strip being so arranged that the contacting of the engaging surface with the loose flange tends to widen the angle between the flanges against the effort of the strip to maintain its normal angle.

2. The combination with a frame or casing, of a weather-strip constructed of resilient material, and composed of two longitudinal flanges arranged at an acute angle to each other, one of the flanges being secured flat

against the frame or casing and arranged against the free edge of the door or window when the latter is closed, and the other flange 20 being movable and extending outward from the frame or casing and arranged to be automatically bent backward to a position at right angles to the attached flange by a door or window in closing, the said movable flange 25 engaging one of the side faces of the door or window when the latter is closed.

In testimony that I claim the foregoing as my own I have hereto affixed my signature in the presence of two witnesses.

WILLIAM H. ETTER.
